PORTABLE GAS TANK

James P. Parker, Cambridge City, Ind., assignor to
Golay & Co., Inc., Cambridge City, Ind.

Filed Aug. 29, 1961, Ser. No. 66,530

Term of patent 14 years

(Cl. D81—2)

FIG. 1 is a side elevational view of a portable gas tank showing my new design;

FIG. 2 is a view in top plan of the tank; and

FIG. 3 is a fragmentary elevational view taken from the right of FIG. 1.

The sides of the tank not shown are substantially the same in appearance as the sides shown except for the lock, handle, and hinge as indicated in FIGS. 1, 2, and 3.

I claim:

The ornamental design for a portable gas tank, as shown and described.
